(57) **CLAIM**

The ornamental design for a photographic light, as shown and described.

DESCRIPTION

FIG. 1 is a perspective view of the photographic light, in its collapsed position, showing my new design;

FIG. 2 is a top view of the photographic light, in its collapsed position;;

FIG. 3 is a side view of the photographic light, in its collapsed position;

FIG. 4 is an end view of the photographic light, in its collapsed position;

FIG. 5 is a perspective view of the photographic light in its partially extended position;

FIG. 6 is a top view of the photographic light in its partially extended position;

FIG. 7 is a side view of the photographic light in its partially extended position;

FIG. 8 is a rear view of the photographic light in its partially extended position;

FIG. 9 is a perspective view of the photographic light in its fully extended position;

FIG. 10 is a top view of the photographic light in its fully extended position;

FIG. 11 is a side view of the photographic light in its fully extended position; and,

FIG. 12 is a rear view of the photographic light in its fully extended position.

The broken lines shown in the drawings illustrate unclaimed portions of the article and form no part of the claimed design.
